SHINGLE OF THE WIDE-SPACED TYPE

Clarence R. Eckert, Englewood, N. J., assignor to
The Barrett Company, New York, N. Y., a corporation of New Jersey

Application July 24, 1931, Serial No. 552,899

2 Claims. (Cl. 108—7)

This invention is directed to roof, wall and other surface coverings and relates more particularly to thick butt shingles adapted to be laid in wide spaced relation.

It is an object of the present invention to provide a thick butt shingle of the felt base type which is provided with a coating of waterproof material, such as asphalt or other bituminous material, a surfacing of granular material on one face of the coating, an additional coating of waterproof material on the surfacing and a second surfacing of granular material applied to the second coating. The initial coating and surfacing cover the entire face of the shingle and the second overlay coating and surfacing cover the entire face except at marginal portions at the sides thereof in which the initial layer of coating and surfacing material is exposed. The marginal portions terminate on a transverse line spaced from the butt edge of the shingle.

It is a further object of the present invention to provide an improved roof covering by the application of thick butt shingles of the above-described type in wide spaced relation in overlapping courses. The marginal portions of shingles of one course function to indicate the proper position of the shingles of the overlying course and thus serve as aligning guides and assist in the ready and accurate application of the shingles on the roof or other surface. In the laying of the shingles, the side edges of the shingles of one course are laid in abutting relation with the inner edges of the marginal portions of the underlying pair of shingles. Preferably, but not necessarily, the second overlay coating and surfacing is made of an aggregate thickness equal to that of the base of the shingle including the initial coating and surfacing. Hence, when two courses of shingles are associated in the manner indicated, the top of the intermediate thick portion of the shingles of an underlying course lies in the same plane as the top of the marginal or thin portions of the shingles of an immediately overlying course and provides a plane surface support for the forward edges of the shingles laid to overlie those in the aforementioned overlying course. Thus, all tendency of the overlapping portions of the overlying shingles to sag is prevented. Further, the thickened intermediate portion of the shingles lends rigidity to the element throughout their length and resists sagging of the elements.

Still a further object of this invention is to provide a process whereby shingles of the above-described type may be conveniently, efficiently

and quickly manufactured in a continuous manner.

The shingle embodying the principles of the present invention is preferably of general rectangular shape and is formed from a web or sheet of conventional roofing felt impregnated and coated with an asphaltic or bituminous composition and surfaced with crushed slate, gravel, slag, silica or other mineral material, hereinafter termed "grit". A second layer of coating material, such as asphalt or other bituminous material, is applied to the entire surface of the coated and surfaced web with the exception of predetermined areas in which the initial surfaced coating is left uncoated. While this second coating is still soft and plastic, grit, either of the same color or fineness or of a different color or fineness from the first layer of grit, is then showered onto the web and adheres only to the cementitious second layer of coating material applied. The web is thereafter severed along longitudinal lines extending through the median lines of the areas of the web wherein the initial surfaced coating is exposed and on transverse lines midway between said areas to form individual thick butt shingles.

The individual shingles thus formed are provided with an initial layer of coating and surfacing material over substantially their entire upper surface and a second layer of coating and surfacing material over substantially the entire surface of the shingle to be exposed and the remaining portion of the upper surface except at marginal areas disposed at the opposite transverse edges of the shingle, the marginal areas terminating on a transverse line spaced from the lower edge of the shingle. The marginal areas which are not provided with the secondary layers of coating material and grit form depressed areas relative to the remaining surface of the shingle.

The individual shingles thus formed are adapted to be laid in wide spaced relation with other shingles in overlapping courses. When so laid, and considering any three courses from bottom to top of the roof, the depressed areas, i. e., the marginal areas of adjacent shingles in the second course combine with the thick or elevated portion of the shingles of an underlying or first course to provide a substantially plane surface support for the butt edges of the shingles of the third course overlapping the adjacent shingles. Hence, the butt edges of the shingles are disposed and supported in one plane and not allowed to sag. The thickened portion of the shingle of the

first or underlying course which cooperates with the marginal edges of the shingles in the second course above to support the butt edges of the shingles in the third course above, seals the opening formed beneath the butt edge of the shingles in the third course and prevents the ingress of rain, snow and other erodents.

For a more detailed description of the present invention, reference is made to the accompanying drawing which, it will be understood, is illustrative of the preferred embodiment of the invention and is not intended to limit the scope of application of the invention to the precise embodiment shown.

15 In the drawing—

Fig. 1 is a side elevation showing, somewhat diagrammatically, apparatus for the manufacture of the shingle of this invention;

20 Fig. 2 is a detailed view of the coating roll employed for the application of the second coating;

Fig. 3 is a plan view of the web from which the shingle of this invention is cut immediately after it has been submitted to the second coating and surfacing operations;

25 Fig. 4 is a plan view of an individual shingle embodying this invention;

Fig. 5 is an enlarged cross section of the shingle of Fig. 1 taken on the line 5—5 of Fig. 4 and showing the relation of the depressed and elevated portions on the upper or exposed face of the shingle;

30 Fig. 6 is a plan view of a portion of a roof covered with the shingles of my invention laid in wide spaced relation and in overlapping courses; and

35 Fig. 7 is an enlarged section taken on the line 7—7 of Fig. 6 showing the shingles laid in wide spaced relation with the front edges of each shingle effectively sealed against the ingress of the elements.

40 With reference to Fig. 1, the shingle of the present invention is formed from a longitudinal sheet or web 11 of conventional roofing felt or other fibrous material saturated or impregnated with an asphaltic or other bituminous composition. A seal-back coating 12 of asphalt or like material (Fig. 5) is applied to the rear surface of the saturated felt 11 to render the felt waterproof and resistant to moisture. To prevent adherence to the seal-back coat 12 of each shingle to adjacent shingles when packed or otherwise formed in bundles, a layer 10 of grit of comparatively fine particles such as flaked mica or sand is applied to the seal-back coat.

45 The saturated felt 11 with its seal-back coat 12 and the grit layer 10 uppermost is passed between rollers 13 and 14 arranged in superposed relation, as shown in Fig. 1. Roller 14 is partially submerged in a tank 15 of asphalt or like bituminous material maintained in a liquid state. The bituminous material adhering to the roller 14 during its rotation in the tank 15 is transferred to the felt 11 and forms an adhesive layer 17 thereon of uniform thickness by reason of the pressure exerted by the roller 13. The position of the felt 11 is now reversed by passing it around a guide roller 16 so that the surface bearing the adhesive layer 17 is uppermost. From the guide roller 16, the felt passes beneath a hopper 18 charged with grit, which may be of one color or a mixture of colors. The grit is showered in a continuous stream upon the adhesive layer 17 of the felt 11 and forms a protective layer 21 thereon. The coated and surfaced felt is passed

5 around guide rollers 22 and 23 so that any excess grit not adhering to the adhesive layer 17 of the felt 11 will fall back into the hopper 18 and become available for further application. Rollers 22 and 23 function to press the grit layer 21 into coating 17 so that the grit particles will become partially embedded in the adhesive layer 17.

6 The thus surfaced and coated felt 11 may then be passed around a series of cooling rollers 24 to harden and set the coating layer 17 thereon, the grit layer 21 becoming firmly embedded 10 therein. From the coating rollers 24, the base 11 is again reversed by means of suitable guide rollers and is passed between coating rollers 25 and 26. Roller 26 is partially submerged in a tank 27 containing asphalt or like bituminous 15 material, is rotatably mounted therein and is arranged to contact with the surfaced layer 21 of the felt base and applying coating material to selected or predetermined areas of the base. This selective application is due to the novel 20 design of the roll 26, as shown in detail in Fig. 2. Two circumferential series of interior rectangular shaped slots 28 are formed in spaced relation from each other and from the ends of the roll in the face thereof, the individual slots being 25 equally spaced around the periphery of the roll. A circumferential series of rectangular shaped slots 29 of equal length but of one-half the width of slots 28 is formed in each end of the roll. It will be noted that the ends of the slots 28 and 30 29 are in alignment along lines running parallel to the axis of the roller 26. By reason of this arrangement of slots, coating material is transferred to the layer 21 of felt base 11 to form an adhesive or second coating layer 31 which has 35 rectangular spaced areas 32 arranged in rows widthwise of the sheet, adjacent rows being spaced from each other through which areas 32, the layer 21 of grit is visible. The design of the roll 26 will necessarily vary depending upon the width of the sheet from which the shingles are cut and the dimensions of the shingles.

40 In the passage of the resultant coated felt base over guide roller 33 the sheet is reversed to bring the adhesive layer 31 uppermost. While 45 the coating 31 is still soft and plastic, the base is passed beneath a hopper 34 charged with grit of the same color or of a contrasting color to the grit in hopper 18. By means of a feed roll 35, the grit is showered upon the coated felt base 31 beneath and adheres only to the adhesive layer 31 and not to the uncoated portions of layer 21 which are not cementitious. The thus surfaced sheet is then passed around press rolls 36 which serve to partially embed the grit layer 37 in 50 the coating 31 and is then reversed in its passage about roll 38 to cause excess grit particles to fall back into hopper 34.

55 The felt base after having thus been twice coated and surfaced as above described, is cut 55 as shown in Fig. 3 along transverse lines 38 which lie midway between the rectangular areas 32 having only the initial coating and surfacing thereon and along transverse lines 39 which pass midway through the rectangular areas 32. The 60 felt 11 is also severed along longitudinal lines 41 which pass through the longitudinal median lines of the rectangular areas 32. The cutting may be accomplished by a rotating cutting roll having the cutting knives arranged thereon.

65 Shingle 42, shown in detail in Figs. 4 and 5 is thus formed. It will be noted that the shingle is provided with the seal-back coating 12 surfaced or dusted with a layer 18 of comparatively fine grit or sand to render it non- 70 75

cementitious. The opposite face of the shingle or the face which is intended to be uppermost when the shingle is laid is provided with a comparatively thick layer 17 of asphalt or the like which is uniformly applied to the entire face of the shingle. The layer 21 of grit is pressed therein to some extent to partially embed the grit particles therein and obtain a comparatively level surface.

10 The second layer 31 of coating material completely covers the end 43 of the shingle 42 which is intended to be exposed and also covers the remaining portion of the upper surface of the shingle with the exception of marginal areas 44 and 45 which extend along the transverse side edges of the shingle from the upper edge thereof to a transverse line spaced from and substantially parallel to the lower edge thereof. Thus it will be noted that the marginal areas 44 and 45 are relatively depressed with respect to the remaining surface of the shingle, which relation functions in the laying of the shingle in a manner to be hereinafter described. Preferably, but not necessarily, the second or overlay coating 25 of asphalt or other bituminous material is made thicker than the initial coating layer 17 and coarser grit particles are used for surfacing the second coating than those applied to the initial coating, so that the aggregate thickness of the 30 second coating and surfacing is approximately equal to the thickness of the coated and surfaced felt base.

The manner of laying the shingle of my invention is best explained by reference to Figs. 6 and 7 wherein individual shingles are shown laid on a portion of a roof, the shingles being laid in wide spaced relation in overlapping courses. With particular reference to courses A, B and C of Fig. 6, the individual shingles of course C are laid in spaced relation such that each individual shingle of course B will fit within the depressed marginal areas 44 and 45 of two adjacent shingles of course C, thereby being positively and accurately aligned both horizontally and vertically 45 with reference to the roof and adjacent courses of shingles. Each individual shingle of course A is laid in a like manner by means of the depressed marginal areas 44 and 45 in the adjacent shingles of course B. It will be noted that the 50 upper or unexposed surface of each shingle of course C lies in substantially the same plane as the depressed marginal areas 44 and 45 of the shingles of course B so that the lower or exposed end of each shingle of course A rests on a substantially plane supporting surface indicated by the reference numeral 51 in Fig. 7. The upper thickened portions of the shingles of course C not only support the shingles of course A so as to prevent sagging thereof, but also effectually 55 seal the opening which would otherwise be formed by the butt end of the shingles of course A bridging the space between adjacent shingles of course B.

60 The longitudinally extending area of the second layer 31 of coating material and the second layer 37 of surfacing material applied to each shingle further serve to strengthen the shingles and provide a more rigid structure resistant to sagging tendencies and which assists 65 in the support of overlying shingles.

While the manner of laying the shingle of this invention has been described with reference to only three courses of shingles, it is to be understood that the same manner of laying is prac-

ticed throughout the roof or other surface to be covered.

Grit or surfacing material may be omitted from the areas 44 and 45 of the shingle or the first layer 21 of surfacing material entirely 5 omitted, leaving the coating 17 exposed on the depressed marginal areas 44 and 45. Thus, when the shingles are laid, as shown in Figs. 6 and 7, the coating material upon the areas 44 and 45 will adhere to the contacting areas of overlying 10 shingles and more efficiently seal the joint between adjacent shingles. If desired, cementitious material such as bitumen may be applied to the depressed portions 44 and 45 to cause the overlying shingles to bond therewith. Grits of 15 different colors may be applied to the individual shingles to obtain different color effects.

This invention comprehends shingles formed from other than a felt base. For example, shingles of a molded type composed of cement 20 asbestos or clay, pitch or mastic compositions may be formed in the shape of the shingle and laid in the manner described herein.

The advantages of the shingles of my invention are readily apparent. The thickened exposed end and intermediate portions of the shingle results in increased rigidity, improved weathering properties and artistic deep shadow effects, particularly as compared with the flexible shingles now marketed. Laying the shingle 25 in wide spaced relation as shown in Fig. 6 with approximately two-thirds of the shingle exposed results in a marked economy in the number of shingles necessary to cover a given surface. The feature of having the intermediate thick portion 30 of the shingles of a lower course cooperate with the depressed portions of the overlying shingles to form a plane support and seal the forward edges of the shingles bridging the overlying 35 shingles improves the weathering properties of the resultant roof. Further, effectual support is provided for the thick butt edge of each shingle, thus eliminating sagging which is undesirable because of the consequent bending and cracking 40 of the felt base and the coating and surfacing 45 layers of the shingle along the bending lines.

It is to be understood that my invention is not restricted to the present disclosure.

I claim:

1. A shingle of the wide spaced type adapted 50 to be laid in overlapping courses with other like shingles comprising a flexible fibrous base coated with bituminous material, said shingle having a second layer of coating material applied thereto except on marginal areas at the sides thereof, 55 said areas extending from the upper end of the shingle to a transverse line spaced from the lower end thereof a distance equal to the amount of the shingle exposed by the overlapping shingles of an overlying course, granular surfacing material partially embedded in said second coating layer whereby the top surface of said shingle except said marginal areas lies in one plane and the surface of said marginal areas lies in another 60 plane below said first plane, said marginal areas being of a thickness equal to about one-half the thickness of the contiguous portions of the shingle whereby overlapping marginal areas of two shingles form with contiguous portions of the shingles a substantially plane supporting surface for a third shingle for preventing sagging 65 thereof.

2. A roof composed of shingles laid in wide 70 spaced relation in overlapping courses, each 75

shingle comprising a fibrous base having one surface coated with bituminous material and grit particles partially embedded in said bituminous material, a second layer of bituminous material 5 completely covering said grit particles except at marginal areas at the sides thereof, said areas extending from the upper end of the shingle to a transverse line spaced from the lower end thereof a distance equal to the amount of the 10 shingle intended to be exposed by the overlapping shingles of an overlying course, and a second layer of grit partially embedded in said second coating, the combined thickness of said second coating layer and said second layer of grit being

substantially equal to the combined thickness of said fibrous base and said first coating and surfacing layers, said first surfacing layer lying in a plane below said second surfacing layer, the shingles of each course being laid in wide spaced relation such that marginal areas of a pair of shingles of each course receive the side edges of an overlying shingle in the course immediately above, the marginal areas of the shingles of the overlying course and a portion of the shingles 10 of the underlying course presenting a substantially plane support for the shingles in the course overlapping the said overlying course.

CLARENCE R. ECKERT.
